UNITED STATES PATENT OFFICE.

JOHN ABSALOM WILLIAMS, OF AURORA, MISSOURI.

SCARIFIER ATTACHMENT FOR ROAD-GRADERS.

1,352,714.

Specification of Letters Patent. Patented Sept. 14, 1920.

Application filed January 14, 1920. Serial No. 351,839.

To all whom it may concern:

Be it known that I, JOHN A. WILLIAMS, a citizen of the United States, and a resident of Aurora, in the county of Lawrence and State of Missouri, have invented certain new and useful Improvements in Scarifier Attachments for Road-Graders, of which the following is a specification.

My invention relates to road graders and more particularly to a scarifier attachment therefor.

A purpose of my invention is the provision of a scarifier of simple and efficient construction having teeth of a form to permit additional metal being welded thereon when they become worn or broken, thereby eliminating any waste of the metal.

It is also a purpose of my invention to provide a scarifier including a slotted block having projections co-acting with clamping members for effectively securing the teeth in adjusted position within the block, the block being provided with means for attaching it to any standard form of road grader so that the scarifier as a unit is capable of vertical adjustment.

I will describe one form of scarifier embodying my invention and will then point out the novel features thereof in claims.

In the accompanying drawings,

Figure 1 is a view showing in phantom one form of road grader having applied thereto one form of scarifier embodying my invention.

Fig. 2 is a longitudinal sectional view of the scarifier shown in Fig. 1, with certain of the teeth and clamping members removed therefrom.

Fig. 3 is a view showing in rear elevation, the scarifier shown in Fig. 2.

Fig. 4 is a view showing an end elevation, of the scarifier shown in the preceding views.

Fig. 5 is a detail perspective view of one of the clamping members shown in the preceding views.

Fig. 6 is a detailed perspective view of one of the teeth used in the scarifier.

Similar reference characters refer to similar parts in each of the several views.

Referring specifically to the drawings, the scarifier is here shown as comprising a block B which is slotted longitudinally at its rear side to provide a channel 15 for receiving clamping members designated generally at C. As shown in Fig. 2, the

block B is provided with rectangular openings 16 which are disposed on an incline with relation to the vertical and are preferably arranged in pairs to slidably accommodate teeth T. As shown in Fig. 6, each tooth T is formed of a single length of metal of rectangular contour in cross section with one end thereof pointed by beveling two of its faces so that the point terminates at one corner of the tooth. The tooth T is provided with notches 18 for co-action with the clamping member C in securing the teeth within the block.

As shown in Figs. 2 and 3, the rear side 70 of the block B is shaped to provide at intervals companion projections 19 and 19^a which are disposed upon opposite sides of the channel 15. These projections are provided with oblique surfaces and are designed to form abutments or bearing surfaces for the actuating means for the clamping members C and to bring each clamping member in line with the position of the particular tooth it is to hold. As illustrated 80 to advantage in Fig. 5, each clamping member C comprises a shank portion 20 bent at one of its ends to provide a ring 21, its opposite end being screw threaded to accommodate a clamping nut 22. The nut 22 is 85 designed for effecting a longitudinal adjustment of the ring 21, and in the applied position of the clamping member, as clearly shown in Fig. 2, one of the teeth T extends through the ring 21 and is adapted to be 90 locked against movement within the corresponding opening 16 by a rearward movement of the ring so as to cause the latter to firmly engage the teeth within one of the notches 18. This is effected through the medium of the nut 22 which bears against the corresponding pair of projections 19 and 19^a so that when it is rotated in the proper direction upon the shank 20, the 95 rearward feeding of the shank is effected which in consequence causes a rearward movement of the ring 21. With the rearward movement of the ring, it engages the tooth in any one of the notches 18 depending upon the adjustment of the tooth, it 100 being understood that the tooth is manually adjusted within the block prior to the movement of the ring to clamping position. A plate 23 is slidably fitted upon the shank 20 of the clamping member C and is interposed between the projections 19 and 19^a 105 and the nut 22. This plate 23 serves as a

washer for the nut and at the same time properly positions the shank 20 within the channel 15. As shown in Fig. 1, the scarifier is provided with six vertical teeth which are arranged in sets of three, with the teeth of one set disposed in divergent relation to the teeth of the other set, and all of the teeth inclined with relation to the vertical. With the teeth arranged in this manner, it will be clear that the projections 19 and 19^a serve to maintain the clamping members in angular position with relation to the teeth T so that the ring of any one clamping member will properly engage the shank of the corresponding tooth to firmly hold the latter in position. The projections 19 and 19^a also provide faces to receive the plates 23 normal to the stress of the clamping members C.

As illustrated to advantage in Figs. 2 and 4, the opposite ends of the block B are recessed longitudinally for a short distance to provide sockets 24 for removably receiving certain of the teeth T and for supporting the same in a horizontal position. The teeth T are locked in adjusted position within the sockets 24 by pins 25 which intersect the sockets at right angles so that a portion of the pins when in the applied position will be disposed within one of the notches 18 of the teeth to effect a secure locking of the teeth within the block.

Although I have herein shown and described only one form of scarifier embodying my invention, it is to be understood that various changes and modifications may be made herein without departing from the spirit of the invention and the spirit and scope of the appended claims.

Having shown and described my invention, what I claim is:

1. In a scarifier, a block having a channel formed therein and openings in the walls of said channel inclined to the edges of the block, teeth slidable through said openings and adapted to bridge said channel, oblique projections formed on the edges of the walls of said channel, and clamping means working within said channel engaging said teeth at a point within the channel and having members engaging said projections which provide faces normal to the line of stress of said means.

2. In a scarifier, a block having a channel formed therein and rectangular openings in the walls of said channel inclined to the edges of said block, teeth of rectangular contour in cross section slidably fitted within said openings in a manner to bridge said channel, oblique projections formed on the edges of the walls of said channel, and clamping means working within said channel and having members engaging the projections which provide faces normal to the line of stress of said means, each of said members comprising, a ring adapted to embrace a tooth at a point between the channel, a shank formed integral with said ring and having a threaded portion extending exteriorly of the channel, a nut on the threaded portion of said shank, and a plate movable on the shank, said plate spanning certain of the projections and adapted to be engaged by said nut for causing the same to move said shank and ring in the direction of the projections.

JOHN ABSALOM WILLIAMS.
